A. F. BLECHSCHMIDT,
COMBINATION LOCK,
APPLICATION FILED APR. 18, 1918.

1,385,810.

Patented July 26, 1921.

By Arthur H. Ewald,
Attorney.

UNITED STATES PATENT OFFICE.

ARTHUR F. BLECHSCHMIDT, OF DAYTON, KENTUCKY, ASSIGNOR OF ONE-HALF TO
WALTER E. BEATTY.

COMBINATION-LOCK.

1,385,810.

Specification of Letters Patent.

Patented July 26, 1921.

Application filed April 18, 1918. Serial No. 229,251.

To all whom it may concern:

Be it known that I, ARTHUR F. BLECHSCHMIDT, a citizen of the United States, and a resident of Dayton, in the county of Campbell and State of Kentucky, have invented certain new and useful Improvements in Combination-Locks, of which the following is a full, clear, and exact description, reference being had to the accompanying drawings, forming a part of this specification.

My invention relates to combination locks, and particularly to mechanism in such locks whereby the unwarranted withdrawal of the locking bolts is prevented.

In combination locks as at present constructed, it is the practice for the bolt stop, whereby the locking bolts are prevented from withdrawal from locking position, to work directly into the notches in the tumblers on the dial stem. It is thus possible, by breaking off the dial, to remove the tumblers, and the locking bolts may thus be withdrawn and the door unlocked. The chief object of my invention is to provide means intermediate the tumblers and driver on the dial stem for holding the locking bolts in position, thus obviating the possibility of unlocking the bolts by the removal of the dial, etc.

A further object of said invention is to provide means for automatically locking the intermediate mechanism between the locking bolts and tumblers upon the removal of the tumblers, thus further insuring the security of the lock.

Another object of my invention is to provide simple and convenient means whereby the combination of numbers for the unlocking of the lock may be easily changed, and whereby a greater range of variation in the changes is obtained.

Other objects of said invention will appear from the following description thereof.

In the drawings:

Figure 1 is a rear elevation of a combination lock constructed in accordance with my invention, the rear wall of the lock case being broken away to disclose the mechanism;

Fig. 2 is a section of a portion of the lock;

Fig. 3 is a rear elevation of the bolt check in another position;

Fig. 4 is a section of a portion of the adjustable driver for the operation of the tumblers;

Fig. 5 is a section of the adjustable ring constituting a part of said driver;

Fig. 6 is a rear elevation of Fig. 5;

Figs. 7 and 8 are sectional views of the parts of the adjustable tumblers;

Fig. 9 is a rear elevation of one of the tumblers.

Fig. 10 is a sectional view of the combination mechanism.

The numeral 1 indicates the lock case, 65 which constitutes a housing for the locking mechanism. Movable mounted in the case 1, by means of a bolt and slots 2 and 3, is a locking bolt frame 4 having a vertical portion 5 to which the locking bolts 6 are secured; the said bolts being arranged to operate through openings in the end of the case and to engage openings at the side of the door (not shown) to lock the door in the usual manner. The frame 4 is pivotally 75 secured to an arm 7 carried by a rotatable shaft 8, the shaft 8 being rotatable by any of the ordinary means at the front of the door for the operation of the locking bolts. Integrally formed with the bolt frame is a 80 bolt stop 9, which is arranged to engage in an opening 10 in a bolt check 11. The bolt check, 11, which comprises a block of metal, or other suitable material, is mounted on, or integrally formed with, arms 12, by means 85 of which it is slidably secured to the case 1, bolts 13 extending through slots in said arms.

Pivots secured at 14 to the case 1 is a tumbler arm 15. One end of the arm 15 is 90 pivotally secured to one of the arms 12 of the bolt check 11. The other end of the tumbler arm is bent upwardly and is arranged to engage in the notches in the driver and tumblers of the combination 95 mechanism.

Rotatably mounted in the case 1 in the usual manner is the usual dial shaft, or stem 16, the front end of which has secured to it the usual dial 17, for governing the 100 manipulation of the tumblers. Secured to the inner end of the dial stem 16 by means of a threaded stem 17^a and flat key 18 is a driver disk 19, the face of which is provided with an indicating point 20. Arranged to be 105 secured to the disk 19 in any suitable adjustment therewith, is a ring 21, the disk and ring being both rabbeted to form the joint therebetween, as shown in Figs. 4 and

5. The contacting vertical faces of the 110

rabbets are toothed to provide rigid engagement between the parts in the desired adjustment. The face of the ring is provided with an annular scale, as shown in Fig. 6, 5 and adjustments between the disk and ring are effected by use of the said scale and the indicating point on the disk. The outer edge of the ring 21 is provided with a single notch 22, into which the end of the tumbler 10 arm 15 is adapted to enter when said notch is properly positioned. Loosely mounted on the stem 16 is any suitable number of tumblers, each comprising a disk 23 and ring 24 constructed to be secured together by means 15 of screws and a toothed rabbeted joint identical with that between the disk 19 and ring 21. The disk 23 and rings 24 are also provided with indicating points and annular scales respectively, identical with those on 20 the disk 19 and ring 21. The tumblers are operated by means of the studs 25 in the usual manner. Each of the tumblers is provided with a notch 26 into which the tumbler arm 15 is adapted to enter when the 25 notches are properly positioned.

Movably mounted in the case 1 in front of the bolt check 11, is a pin 27; a spring 28 resting in a recess in the case and mounted on the shank of said pin, places the pin in 30 tension against the front of the bolt check, as shown in Fig. 2. A head 28^a prevents the removal of the pin from the case wall. The pin 27 is so positioned, relative to the bolt check, that, when said check is in its 35 lowermost position, it will clear the pin and permit the spring to force it outwardly over the bolt check, thus preventing the raising of the bolt check, for the purpose herein-after described.

40 The operation of the lock is as follows: In Fig. 1 I have shown the parts in unlocked position; in this position, the bolts are withdrawn from the keepers (not shown), the bolt stop 9 being in the recess 10 of the bolt check 11, its entrance therein being permitted by the lowering of said check to the position shown because of the entrance of the end of the tumbler arm into the notches of the driver and tumblers. To lock, the shaft 45 8 is rotated so as to throw the bolts 6 forward into their keepers; the dial is then spun, rocking the tumbler arm and raising the bolt check 11 so that the lower portion thereof is opposite the bolt stop 9. To unlock, the combination is operated in the 50 usual manner until all of the notches are in alinement over the end of the tumbler arm 15; the weight of the check 11 will cause it to drop when thus permitted, and the bolts 55 may then be withdrawn, the stop 9 entering the recess 10 in the bolt check. Suppose now, as frequently happens in the breaking of safes, that the dial is broken off and the driver and tumblers removed. The tumbler 60 arm 15 is thus released, and the bolt check 65

consequently permitted to fall by its own weight; there being no obstacle now in the way of the arm 15, as is ordinarily presented by the base of the notches in the tumblers, the check 11 falls until the upper portion 70 thereof, above the recess 10, is opposite the bolt stop 9; the bolts are thus as effectually locked as when secured by the lower portion of said check. Furthermore, when in this position, the check 11 clears the pin 27, 75 which is automatically forced outwardly over the check, thus preventing its being raised until the pin has been withdrawn. As will be seen, the provision of the intermediate bolt check, thus effectually secures 80 the lock against unwarranted tampering, as the removal of the dial and tumblers only serves to secure the locking bolts even more securely in locked position.

As will be seen, also, the making of the 85 driver of two parts relatively adjustable by means of the notched rabbeted joint together with the similar construction of the tumblers, gives a wide range of variations in the 90 adjustments of the combination as well as great facility in the making of changes, since it is only necessary to remove the 95 securing screws in the driver or one or more of the tumblers, as may be desired, rotate the ring or rings on the disks and resecure the parts together.

It will be understood that various modifications of the details of construction above set forth may be made without departing from the principles of the invention, and I 100 do not therefore limit myself to said details, but deem my invention to be co-extensive with a fair and liberal construction of the appended claims.

Having thus described my invention, what 105 I claim as new and desire to secure by Letters Patent, is:—

1. In a lock, the combination with locking bolts and tumblers, a bolt stop in connection with said bolts, a bolt check slidably mounted intermediate said tumblers and said bolt stop, said bolt check having an opening 110 adapted to receive said bolt stop to permit the operation of said bolts, a tumbler arm pivotally mounted adjacent said bolt check 115 and arranged to maintain a desired relation between said tumblers and said bolt check, means whereby upon the removal of said tumblers, when the bolts are in locking position, said bolt check is moved gravitationally, and means whereby when so positioned it is adapted to secure the bolts in such position, and means arranged to engage said bolt check when so positioned gravitationally to prevent raising the bolt check.

2. In a lock, the combination with locking bolts and tumblers, a bolt stop in connection with said bolts, a bolt check slidably mounted intermediate said tumblers and said bolt stop, said bolt check having 120 125 130

an opening adapted to receive said bolt stop to permit the operation of said bolts, a tumbler arm pivotally mounted adjacent said bolt check and arranged to maintain a desired relation between said tumblers and said bolt check, means whereby upon the removal of said tumblers, when the bolts are in locking position, said bolt check is moved

gravitationally, means whereby when so positioned it is adapted to secure the bolts in such position, and a spring pressed pin arranged to engage over said bolt check when so positioned gravitationally to prevent raising the bolt check. 10

ARTHUR F. BLECHSCHMIDT.
